CLAIM

The ornamental design for a towel onesie, as shown and described.

DESCRIPTION

FIG. 1 is a perspective view of the towel onesie.

FIG. 2 is a front view thereof.

FIG. 3 is a back view thereof.

FIG. 4 is a top view thereof.

FIG. 5 is a bottom view thereof; and,

FIG. 6 is a right side view thereof. A left side is not shown but is a mirror image of the right side view shown in FIG. 6.

The broken lines shown in the drawings depict portions of the towel onesie that form no part of the claimed design.
